[57] CLAIM

The ornamental design for a combined trash containers and cart therefor, as shown and described.

DESCRIPTION

FIG. 1 is a perspective view of a combined trash containers and cart therefor showing my new design, the lids of the containers being removed and the containers being elevated from the bottom of the cart for clarity of illustration;

FIG. 2 is a side elevational view thereof, the opposite side elevational view being a mirror image of that shown;

FIG. 3 is a rear elevational view thereof;

FIG. 4 is a front elevational view thereof; and

FIG. 5 is a side elevational view of the combined trash containers and cart therefor showing a second embodiment, the difference from the first embodiment being in an expanded cart having three trash containers thereof.
